CLAIM

We claim the ornamental design for a personal enclosure, as shown and described.

DESCRIPTION

FIG. 1 is an upper right perspective view of a personal enclosure according to an embodiment of the personal enclosure.

FIG. 2 is an upper right perspective view of the personal enclosure shown in FIG. 1 with the door in an open position.

FIG. 3 is a front elevation view of the personal enclosure shown in FIG. 1.

FIG. 4 is a back elevation view of the personal enclosure shown in FIG. 1.

FIG. 5 is a right side elevation view of the personal enclosure shown in FIG. 1.

FIG. 6 is a left side elevation view of the personal enclosure shown in FIG. 1.

FIG. 7 is a top view of the personal enclosure shown in FIG. 1.

FIG. 8 is a bottom view of the personal enclosure shown in FIG. 1.

FIG. 9 is a cross-sectional view taken along line 9-9 in FIG. 7 showing the interior left side wall of the personal enclosure shown in FIG. 1.

FIG. 10 is a cross-sectional view taken along line 10-10 in FIG. 7 showing the interior right side wall of the personal enclosure shown in FIG. 1.

FIG. 11 is a cross-sectional view taken along line 11-11 in FIG. 7 showing the interior rear wall of the personal enclosure shown in FIG. 1.

FIG. 12 is a cross-sectional view taken along line 12-12 in FIG. 3 showing the interior bottom surface of the personal enclosure shown in FIG. 1.

FIG. 13 is a cross-sectional view taken along line 13-13 in FIG. 3 showing the interior top surface of the personal enclosure shown in FIG. 1.

FIG. 14 is a cross-sectional view taken along line 14-14 in FIG. 7 showing the interior front wall of the personal enclosure shown in FIG. 1.

FIG. 15 is a cross-sectional view taken along line 15-15 in FIG. 5 showing the interior bottom surface and the top surface of the desk of the personal enclosure shown in FIG. 1.

FIG. 16 is an upper right perspective view of a second embodiment of a personal enclosure.

FIG. 17 is an upper right perspective view of the personal enclosure shown in FIG. 16 with the door in an open position.

FIG. 18 is a front elevation view of the personal enclosure shown in FIG. 16.

FIG. 19 is a back elevation view of the personal enclosure shown in FIG. 16.

FIG. 20 is a right side elevation view of the personal enclosure shown in FIG. 16.

FIG. 21 is a left side elevation view of the personal enclosure shown in FIG. 16.

FIG. 22 is a top view of the personal enclosure shown in FIG. 16.

FIG. 23 is a bottom view of the personal enclosure shown in FIG. 16.

FIG. 24 is a cross-sectional view taken along line 24-24 in FIG. 22 showing the interior left side wall of the personal enclosure shown in FIG. 16.

FIG. 25 is a cross-sectional view taken along line 25-25 in FIG. 22 showing the interior right side wall of the personal enclosure shown in FIG. 16.

FIG. 26 is a cross-sectional view taken along line 26-26 in FIG. 22 showing the interior rear wall of the personal enclosure shown in FIG. 16.

FIG. 27 is a cross-sectional view taken along line 27-27 in FIG. 18 showing the interior bottom surface of the personal enclosure shown in FIG. 16.

FIG. 28 is a cross-sectional view taken along line 28-28 in FIG. 18 showing the interior top surface of the personal enclosure shown in FIG. 16.

FIG. 29 is a cross-sectional view taken along line 29-29 in FIG. 22 showing the interior front wall of the personal enclosure shown in FIG. 16.

FIG. 30 is a cross-sectional view taken along line 30-30 in FIG. 18 showing the interior bottom surface and the top surface of the desk of the personal enclosure shown in FIG. 16.

FIG. 31 is an upper right perspective view of a third embodiment of a personal enclosure.

FIG. 32 is an upper right perspective view of the personal enclosure shown in FIG. 31 with the door in an open position.

FIG. 33 is a front elevation view of the personal enclosure shown in FIG. 31.

FIG. 34 is a back elevation view of the personal enclosure shown in FIG. 31.

FIG. 35 is a right side elevation view of the personal enclosure shown in FIG. 31.

FIG. 36 is a left side elevation view of the personal enclosure shown in FIG. 31.

FIG. 37 is a top view of the personal enclosure shown in FIG. 31.

FIG. 38 is a bottom view of the personal enclosure shown in FIG. 31.

FIG. 39 is a cross-sectional view taken along line 39-39 in FIG. 37 showing the interior left side wall of the personal enclosure shown in FIG. 31.

FIG. 40 is a cross-sectional view taken along line 40-40 in FIG. 37 showing the interior right side wall of the personal enclosure shown in FIG. 31.

FIG. 41 is a cross-sectional view taken along line 41-41 in FIG. 37 showing the interior rear wall of the personal enclosure shown in FIG. 31.

FIG. 42 is a cross-sectional view taken along line 42-42 in FIG. 33 showing the interior bottom surface of the personal enclosure shown in FIG. 31.

FIG. 43 is a cross-sectional view taken along line 43-43 in FIG. 33 showing the interior top surface of the personal enclosure shown in FIG. 31.

FIG. 44 is a cross-sectional view taken along line 44-44 in FIG. 37 showing the interior front wall of the personal enclosure shown in FIG. 31; and,

FIG. 45 is a cross-sectional view taken along line 45-45 in FIG. 33 showing the interior bottom surface and the top surface of the desk of the personal enclosure shown in FIG. 31.

The broken lines illustrate portions of the personal enclosure which form no part of the claimed design. The surface shown broken away horizontally and vertically in the FIGS. 31, 32, and 39 views indicates that anything between the break lines forms no part of the claimed design. The broken line breakaway lines also form no part of the claimed design.
